DRAPERY HANGER

Filed Dec. 6, 1928

UNITED STATES PATENT OFFICE

EDITH SEWELL LEE, OF DALLAS, TEXAS

DRAPERY HANGER

Application filed December 6, 1928. Serial No. 326,421.

This invention relates to hangers and more particularly to hangers for suspending drapery over windows, doors and other places in the interior of a dwelling or building.

5 The invention has for its primary object the provision of a drapery hanger which is capable of moving the drapery or draperies from a window or door opening or placed in position across or over the opening without folding, creasing, rolling or reversing the drapery.

10 The construction and arrangement of the means for carrying out the above object enables the drapery to be moved while in its suspended spread out, or hanging formation and displaying only one side of the drapery at all times.

15 Another object of the hanger lies in its simplicity of construction, including its ease of operation.

20 The improved drapery hanger will be clearly understood from a perusal of the following detailed description, taken in connection with the accompanying drawings, forming part hereof and in which:

25 Figure 1 represents a side elevational view of double doors on the interior of a dwelling and illustrating a pair of the hangers in open and closed position.

30 Figure 2 is an enlarged detail view of one of the hangers and a partial view of one drapery at the right hand door.

Figure 3 is a plan view of Figure 2, and

35 Figure 4 is a partial vertical sectional view, along the line 4—4 in Figure 2.

Proceeding in accordance with the drawings and wherein different numerals are employed to designate the various parts, 1 denotes a door frame in which are swung doors

40 2. The hanger, however, is of course equally applicable to single door openings, window openings, or other openings on the dwelling interior.

The hanger consists of a plate 3, affixed by 45 screws or otherwise, just above the door

frame 1, or above a window frame. The plate 3 has spaced ears 4, between which is pivotally seated a pin 5, the latter carrying an arm 6. The construction in this respect may be varied, however, in any way to provide a means to permit the arm to be swung from side to side.

50 Seated in the outer end of the arm 6 is a bolt 7, and below the bolt and pivotally attached thereto is a bar 8. This bar provides a means for suspending a drapery by means of spaced hooks 10, in connection with cords, wires or the like 11.

55 In operation of the hanger, the drapery is pulled slightly in a lateral side-to-side movement, to remove the drapery from or replace it over an opening. This movement permits the arm 6 and bar 8 to move the drapery to the desired position. The arm 6, as will be obvious from its position and arrangements, 60 swings from its pin 5, while the bar 8, carrying the drapery 9, is thus moved outwardly and then laterally in a line parallel with the front of the door frame. In this manner the drapery is not turned over or reversed but 65 presents the front side at all times. Whether the doors are opened or closed, the draperies will effectually conceal the doors when swung into position. Thus, in Figure 2, the draperies are shown open in full lines and in 70 closed position in dotted lines. Also, the draperies alone may be employed to conceal 75 the door opening, leaving the doors open.

75 The drapery hanger is as effectual for windows, and may be swung in front of a window 80 or against the wall, the front side of the drapery being always in view.

85 Manifestly, the hanger is capable of variation in construction both mechanically and ornamentally, as the arm and bar and other parts may be made of metal, wood or any material to conform to the interior decorations of a room.

90 What is claimed as new is:

A drapery hanger comprising a plate hav-

ing spaced ears adapted to be secured to a window or door frame; an arm pivotally secured between the ears of said plate, said arm adapted to swing freely from side to side; a bolt seated in the outer end of said arm; a bar pivotally attached to said bolt; said bar adapted to swing freely below the pivotally secured arm; spaced hooks on said bar for supporting drapery by the means of cords.

5 0 In testimony whereof I affix my signature.
EDITH SEWELL LEE.
